ADJUSTABLE POLE EXTENSIONS FOR USE IN ELECTROMAGNETIC HARDNESS TESTERS

Robert C. Scott, 340 Common St., Belmont, Mass.

Filed June 16, 1960, Ser. No. 36,667

2 Claims. (Cl. 73—81)

This invention relates to adjustable pole extensions for use in electromagnetic hardness testers of the kind shown and described in U.S. Patent No. 2,693,698, issued November 9, 1954 to Robert C. Scott. That patent describes a hardness tester which is adapted for testing ferromagnetic work pieces having variously formed surfaces, that can be affixed and firmly held by electromagnetic means to the work during the making of hardness tests, and that demagnetizes the work after completion of a test to facilitate removal of the tester from engagement with the work. The electromagnetic means comprises a cylindrical electromagnet having an annular recess to form inner and outer concentric pole cores which contact the work, a coil placed within the recess, and an armature comprising the work piece itself. This arrangement affords a high magnetic force to retain the tester securely in place on the work piece against the mechanical forces exerted during the testing operation.

For conducting hardness tests on a work piece having a surface which is curved or non-planar, my aforementioned patent discloses a shoe adapter, forming an extension of the electromagnet poles, which may be secured to the lower surface of the electromagnet to reduce the cumulative air gap between the electromagnet and the curved work surface, thus increasing the lifting or withholding force to a value adequate to resist the maximum opposing force exerted by a penetrator in making a hardness test upon the work surface. The work-contacting surface of the shoe adapter described forms an arcuate portion of a cylinder having an inherently fixed radius. As a consequence, it is desirable to provide a variety of shoe adapters of differing surface radii of curvature, for conducting tests upon curved work surfaces of differing diameter or irregular form.

The primary object of this invention is to provide improved means for minimizing the air gap between the pole piece of an electromagnetic hardness tester and work pieces having curved or otherwise non-planar surfaces.

It is a further object of this invention to provide improved adjustable pole extension means for use with electromagnetic hardness testers, to accommodate ferromagnetic work pieces having various forms and a wide range of radii of curvature with a minimum cumulative air gap between the hardness tester and the work piece.

An important feature of the invention resides in the provision of auxiliary adjustable pole pieces capable of adjustment not only as to length but also as to the angular posture of the faces which bear upon the work piece. In consequence the work engaging structure of the hardness tester may effectively be modified to conform to the surface contour of a work piece and thereby minimize the air gap.

It is a feature of this invention that the improved pole extension means utilizes a relatively small number of pole extension plates capable of being assembled in a variety of groups to afford a wide range of effective radii of curvature and are effective to minimize the cumulative air gap between an electromagnet and work surfaces of widely varying form.

It is a further object of this invention to provide improved adjustable pole extension means for use with electromagnetic hardness testers, applicable either directly to an electromagnetic structure having planar surfaces, or by means of an improved shoe adapter to a cylindrical electromagnetic structure.

2

Further objects and advantages of my invention will become apparent as the following description proceeds, referring to the accompanying drawing, in which:

FIG. 1 is a view in side elevation of a preferred embodiment of my improved pole extension means, including a shoe adapter for mounting the pole extension plates upon an electromagnetic hardness tester;

FIG. 2 is a top plan view of the pole extension means of FIG. 1;

10 FIG. 3 is a view in side elevation of a set of pole extension plates which are used in various groups to form a portion of the pole extension means;

FIG. 4 is a view in front elevation of one of the plates of FIG. 3; and

15 FIG. 5 is a view in side elevation of a fragmentary portion of an electromagnetic hardness tester of modified form, shown in combination with the pole extension plates.

Referring to FIG. 1, a fragmentary portion 10 of an electromagnetic hardness tester is shown in broken lines, 20 comprising cylindrical electromagnetic means for holding a work piece during a testing procedure, as more fully shown and described in my aforementioned U.S. Patent No. 2,693,698. The electromagnet is designed to provide a lifting or tractive force between the face of the magnet 25 and the surface of a work piece whose hardness is to be measured of sufficient magnitude adequately to resist the maximum opposing force of a penetrator (not shown) which is caused to indent the work surface for determination of its hardness. The work piece, which is ferromagnetic acts as the armature of the magnetic circuit. It is necessary that the magnetic tractive force be sufficiently great to prevent any movement whatever between the face of the magnet and the surface of the work.

The present invention is directed toward the problem 30 of minimizing the cumulative air gap between the face of the electromagnetic hardness tester 10 and work pieces whose surfaces have a variety of forms of radii of curvature. An illustrative work piece of cylindrical form is shown in broken lines in operative relation to the hardness tester. The work piece forms only a tangential line contact with the surface of the electromagnet, and it is therefore desirable to provide pole extension means, especially for the outer pole, to reduce the cumulative air gap between these members, so as to prevent excessive reduction 40 in the magnetic force retaining the work piece in testing position.

In carrying out my invention in part, I provide at 45 least two sets of pole extension means comprising plates 11, 12 and 13, which are more fully shown in FIGS. 3 and 4. The plates are trapezoidal in cross-section, being respectively formed with opposite side edge plane surfaces 11a and 11b, 12a and 12b, and 13a and 13b, each of which forms a different angle with the parallel major surfaces of the corresponding plate. The number of plates in the set and the range in side edge surface angles are not critical to the invention, but I prefer to provide three plates in each set as shown, having angles ranging from approximately 65 to 90 degrees, at 5 degree intervals. For convenience in selection, I prefer to stamp an identifying mark (not shown) on the plates adjacent to each side edge. Each plate is also formed with a pair of mounting slots 14 extending transversely to its side edges, of which one pair in plate 11 is best shown in FIG. 4.

60 Referring again to FIGS. 1 and 2, I provide a shoe adapter 16, having a circular opening 17, for adjustably mounting groups of plates 11, 12 and 13 upon the lower outer surface of the cylindrical hardness tester 10. The shoe adapter and its component parts, and also plates 11, 12 and 13, are made of soft iron or low content carbon steel slowly annealed after machining, in order to pro-

vide a magnetic circuit having maximum flux density and therefore maximum tractive force. On opposite sides thereof, adapter 16 is slotted at 18 and split at 19, to allow for flexing and clamping of the frame. The adapter is secured to the outer pole core surface of the electromagnet structure by a clamping screw 20, received in suitably bored and threaded holes 21 and 22. For supporting the plates, the adapter is formed with plane edge surfaces 23 and 24, which intersect the major surfaces of the shoe frame in parallel lines and converge downwardly toward the work piece. Pre-selected groups of two plates from each set, shown as plates 11 and 12 by way of illustration, are secured to opposite sides of the adapter upon surfaces 23 and 24 by washers 25 and cap screws 26, the screws extending through slots 14 and being threaded into the adapter.

The selection and adjustment of the pole extension plates is made with reference to the diameter or form of the work piece, to conform to the condition that each of side edge surfaces 11a and 12a, as well as the lower surface of the hardness tester, contact the surface of the work piece tangentially. As used herein, the term "tangentially" is used with reference to a cross-section of the work piece, with which the side edge surfaces form point contact; thus, "tangential" contact is abutment along each point of a line of contact between a side edge surface and the work piece. Thus it will be apparent that in testing a cylindrical work piece whose centerline falls substantially at the intersection of the planes of shoe frame surfaces 23 and 24, plates having side edge surfaces approximately normal to their major surfaces, such as surface 12b, should be selected. When testing larger or smaller work pieces, the side edge surface angles to be selected become more acute. The positions of the plates relative to the shoe adapter 16 are also adjusted to meet the aforementioned condition, and this adjustment is accommodated by relatively moving screws 26 along slots 14 until surfaces 11a and 12a contact the work piece.

The tangential abutment of the side edge surfaces of the pole extension plates upon the work piece minimize the cumulative air gap between the electromagnet and the work piece, thus maintaining the value of the tractive force at a high level adequate to maintain the work piece in position during a hardness test.

It will be apparent that by selecting pole extension plates having side edge surfaces which form appropriate angles relative to their major surfaces, both irregular surfaces and round surfaces whose radii fall in a range between infinity and a minimum whose value depends upon the form and size of the shoe adapter 16, may be hardness tested according to the described mode of operation. An alternate form of pole extension plates comprising a larger number of relatively thin plates with their end faces at right angles relative to their sides may also be used, especially on surfaces where the radius of curvature is relatively large; however, a smaller cumulative air gap is achieved by using relatively few plates, as previously described.

A second embodiment of my improved pole extension means for hardness testers is shown in FIG. 5, in which the shoe adapter is eliminated, and the pole extension plates are mounted directly upon a hardness tester 10'. This device differs from the hardness tester shown in FIG. 1, and described by my aforementioned patent, only with respect to the physical configuration and arrangement of the electromagnet structure, which comprises a rectangularly shaped, rather than cylindrically shaped, flat-faced type electromagnet.

In order that pole extension plates may be fastened directly to the outer pole cores of the rectangular electromagnet structure, this structure is formed with longitudinally-extending parallel flanges 38 and 39 having plane edge surfaces 40 and 41, respectively. These surfaces correspond in function to surfaces 23 and 24 in the shoe adapter of the embodiment shown in FIG. 1, and eliminate the need for such an adapter in the rectangular electromagnet structure. Groups of plates 11' and 12' are secured directly to the surfaces 40 and 41 by means of washers 25' and screws 26'. The construction and operation of the hardness tester and the pole extension means are otherwise identical with those of the embodiment of FIG. 1. The embodiment of FIG. 5 provides the additional advantage that for electromagnet structures of equal size, the minimum radius of curved surfaces that may be hardness tested is less than the minimum radius of curved surfaces that may be hardness tested with the circular type of electromagnet structure.

Although I have shown and described specific embodiments of my invention for illustrative purposes, it is to be understood that the invention is not limited to the specific mechanical and electrical details described. Various changes and modifications may occur to those skilled in the art without departing from the spirit and scope of the invention, and I therefore intend in the appended claims to cover all such changes and modifications.

What I claim as new and desire to secure by Letters Patent is:

1. In a hardness tester the combination comprising electromagnetic means having a planar face, for engaging a work piece, adjustable mounting means secured to said electromagnetic means and forming two planar side surfaces intersecting the plane of said face in parallel lines, and pole extension means comprising a plurality of ferromagnetic plates each having substantially planar major surfaces and a planar side edge surface, said plates being arranged in two stacked groups, each of said groups being adjustably secured to a corresponding one of the side surfaces of said mounting means, with said side edge surfaces extending outwardly from said face with a common component of direction to engage the surface of a work piece, the plates of each group being slidable relative to one another for adjustment of the relative positions of the side edge surfaces to conform to the contours of a selected work piece, whereby the hardness tester may be engaged and disengaged with a series of similar work pieces without re-adjusting the groups of plates, said side edge surfaces forming various angles with the major surfaces of said plates, the angle of each side edge surface being such as to form tangential contact of the plane of that surface with the surface of the selected work piece.
2. The combination recited in claim 1, in which said side surfaces of said mounting means lie in intersecting planes such that said two groups of plates converge from said face of said electromagnetic means in the direction of extension of said plates therefrom.
